Primary Examiner — Ian Simmons
Assistant Examiner — Rashida Johnson(57) **CLAIM**

The ornamental design for a page turning device, as shown and described.

DESCRIPTION

FIG. 1 is a top, front, right side perspective view of a page turning device showing my new design;
FIG. 2 is a top plan view thereof with pages shown in dashed lines, the pages form no part of the claimed design;
FIG. 3 is a bottom plan view thereof;
FIG. 4 is a left side elevational view thereof, the right side elevational view being a mirror image thereof;
FIG. 5 is a front elevational view thereof with pages shown in dashed lines, the pages form no part of the claimed design; and,
FIG. 6 is a rear elevational view thereof.
